DIELECTRIC STAPLE HEAD

John R. Palmer, West De Pere, Wis., assignor to Pal
Staple Corporation, West De Pere, Wis., a corporation
of Wisconsin

Filed Oct. 15, 1965, Ser. No. 87,501

Term of patent 14 years

(Cl. D26—10)

FIG. 2

FIG. 4

FIG. 1 is a perspective view of a dielectric staple head, showing the top, front, and right end of the new design; FIG. 2 is a bottom plan view thereof;

FIG. 3 is a rear elevational view thereof; and

FIG. 4 is a left-hand elevational view thereof.

A nail is shown in broken lines in FIG. 1 for illustrative purposes only.

I claim:

The ornamental design for a dielectric staple head, as shown and described.
